Filed Oct. 18, 1968, Ser. No. 14,076

Term of patent 14 years

Int. Cl. D29—99

U.S. Cl. D72—1

FIG. 1 is a perspective view of traffic control marker base embodying this new design showing in phantom a tubular member supported thereon;

FIG. 2 is a bottom plan view of the traffic control marker base; and

FIG. 3 is a sectional view taken substantially along the plane represented by the line 3—3 of FIG. 1.

The tubular member is shown in broken lines in FIGS. 1 and 3 for illustrative purposes only.

I claim:

The ornamental design for a traffic control marker base, as shown and described.
